US0D1048571S

(12) **United States Design Patent** (10) Patent No.: **US D1,048,571 S**
 Yu et al. (45) Date of Patent: ** Oct. 22, 2024

(54) **BITE BLOCK**(71) Applicant: **Masimo Corporation**, Irvine, CA (US)(72) Inventors: **Edmond Wing Lun Yu**, Chino Hills, CA (US); **Takuya Idehara**, Sherman Oaks, CA (US); **Mahdi Mohammadi**, Mission Viejo, CA (US); **Chad A. DeJong**, Los Angeles, CA (US); **Nicholas Evan Barker**, Laguna Beach, CA (US); **Naoki Kokawa**, Tustin, CA (US)(73) Assignee: **Masimo Corporation**, Irvine, CA (US)(**) Term: **15 Years**(21) Appl. No.: **29/789,642**(22) Filed: **Oct. 7, 2021**(51) LOC (14) Cl. **29-02**

(52) U.S. Cl.

USPC ..... **D29/108**(58) **Field of Classification Search**USPC D24/176, 181; D29/100, 106, 108, 122
CPC . A63B 71/08; A63B 71/085; A63B 2071/086;

A63B 2071/088; A61C 7/08; F41H 1/08

See application file for complete search history.

CLAIM

The ornamental design for a bite block, as shown and described.

DESCRIPTION

FIG. 1 is a front perspective view of a first embodiment of a bite block embodying our new design;
FIG. 2 is another front perspective view thereof;
FIG. 3 is a back perspective view thereof;
FIG. 4 is another back perspective view thereof;
FIG. 5 is another front perspective view thereof;
FIG. 6 is a front view thereof;
FIG. 7 is a back view thereof;
FIG. 8 is a side view thereof;
FIG. 9 is another side view thereof;
FIG. 10 is a top view thereof;
FIG. 11 is a bottom view thereof; and
FIG. 12 is another front view thereof with additional broken line environment.

FIG. 13 is a front perspective view of a second embodiment of a bite block embodying our new design;
FIG. 14 is another front perspective view thereof;
FIG. 15 is a back perspective view thereof;
FIG. 16 is another back perspective view thereof;
FIG. 17 is another front perspective view thereof;
FIG. 18 is a front view thereof;
FIG. 19 is a back view thereof;
FIG. 20 is a side view thereof;
FIG. 21 is another side view thereof;
FIG. 22 is a top view thereof;
FIG. 23 is a bottom view thereof; and
FIG. 24 is another front view thereof with additional broken line environment.

FIG. 25 is a front perspective view of a third embodiment of a bite block embodying our new design;
FIG. 26 is another front perspective view thereof;
FIG. 27 is a back perspective view thereof;
FIG. 28 is another back perspective view thereof;
FIG. 29 is another front perspective view thereof;
FIG. 30 is a front view thereof;
FIG. 31 is a back view thereof;
FIG. 32 is a side view thereof;
FIG. 33 is another side view thereof;
FIG. 34 is a top view thereof;
FIG. 35 is a bottom view thereof; and,
FIG. 36 is another front view thereof with additional broken line environment.

Broken lines, where shown, are used to illustrate portions of the bite block or environmental subject matter that form no part of the claimed design.
